UNITED STATES PATENT OFFICE.

ARTEMAS L. DAWSON, OF ELK POINT, DAKOTA TERRITORY, ASSIGNOR OF
ONE HALF TO CHARLES H. FREEMAN, OF SAME PLACE.

MACHINE FOR ATTACHING METAL COLLARS TO LAMPS.

SPECIFICATION forming part of Letters Patent No. 289,509, dated December 4, 1883.

Application filed June 1, 1883. (No model.)

To all whom it may concern:

Be it known that I, ARTEMAS L. DAWSON, of Elk Point, in the county of Union, Territory of Dakota, have invented a new and useful Machine for Attaching Metal Collars to Lamps; and I hereby declare the following to be a full, clear, and exact description of the same.

It is intended with this machine to provide
10 a means for attaching collars to lamps, the collars being of the kind and attached in the manner described in my Letters Patent No. 264,633, which were granted to me September 19, 1882, and in my pending application, filed in the
15 United States Patent Office at Washington, April 30, 1883, (Serial No. 93,369.)

In the drawings, Figure 1 is a plan view of my device having various parts broken away to show the internal construction; and Fig. 2,
20 a vertical central section of the same, also showing the mechanism underneath by which the follower is controlled.

A is a hollow horizontal metal shaft, suitably supported within bearings in cross-pieces
25 v u, and carrying near one end, firmly secured thereon, a pulley, B. An endless band connects the latter with suitable driving-power to produce rapid revolution of the shaft A. Inserted in the other end of the hollow shaft
30 A are the blades C, of metal, each made sufficiently broad to cause its edges to project through the slots formed to admit them, one on each side of the shaft, the two being directly opposite to each other. Each blade is ex-
35 tended toward its rear end in an arm, t. Each of the said arms is bent to form an outward-projecting right angle, and is loosely pivoted near the end of the said angular portion to opposite ends, one on each face, of a plate, s,
40 placed transversely through the shaft in horizontal slots formed in line with those first above referred to. The plate s is secured in position by means of a pivoted pin passed through the shaft and through the center of
45 the said plate, to permit a horizontal oscillating movement of the blades C, controlled in its extent by the striking of the edges of the plate s against the vertical sides of the slots, and by the pivotal positions of the said arms upon the
50 said plate s. The forward extremity of each

blade C is formed into a finger, r, bent to a right angle, or nearly so, as at the other extremity, to form a burnisher, the purpose of which will hereinafter be described. Each blade C has securely pivoted to its outer face a 55 link, q. F is a collar encircling the shaft A, recessed on opposite sides of its interior to admit the edges of the blades C, and provided with two slotted projections, p, one on each side in line with the said recesses, to form ful-
60 crums for the arms E E, pivoted therein, as also loosely to the extremity of each link q.

G is a chain, secured at each end to one of the arms E, and passing over pulleys o in the recesses of the collar H through slots, one on 65 each side of the said shaft in line with those previously described, into and along the interior of the shaft A until it meets the rod I, to the extremity of which it is firmly secured. The rod I is confined in its movement within 70 the shaft by means of a pin, n, which passes through a slot, m, in the said rod and also through the shaft near its rear internal extremity, dividing the latter into two equal parts.

K is a lever of the second class, having its fulcrum at x, within a slotted projection from the edge of the frame of the device. Owing to the position of the pin n, which passes through the rod I, the said rod will be caused 80 to revolve with the shaft when such revolution is produced, and, since its movement within the latter is to be controlled by means of the lever K, it must be connected thereto in a manner that will permit its revolution. This 85 is effected by means of a flat pin, l, passing through a hole provided for the purpose in the body of the lever and rigidly secured within a slot in the extremity of the rod. The head k of the pin is sufficiently large to prevent its slipping through the hole in the body of the lever, and is made to revolve within a socket formed underneath the cap i and in the top of the hole in the lever. The lever K is provided with a pin, b, extending through the 90 body of the said lever near the handle thereof, and having its movement within a groove, x', formed in the extremity of the frame of the device.

As before stated, the device is for the pur- 100

pose of firmly attaching collars to neckless lamp-bodies, and its mode of operation is as follows: L is a metal plate provided with an orifice to admit the burnisher r. The said orifice is provided with an annular projection or flange, h, around its forward edge, upon which the collar to be attached fits, and is thus held in position, and from the base of which the outer face of the plate L flares outward sufficiently to 5 form a seat for the rim of the collar. When a collar is to be attached, it is placed upon the annular projection around the orifice in the plate L, when the collarless lamp-body is suitably placed against the wall of the follower D, with 10 the center of its opening directly opposite that of the plate L, and moved by means of the follower (controlled by mechanism hereinafter described) forward until the projecting portion of the collar enters the opening in the 15 lamp-body. During this time the shaft A is rapidly revolving, wherefore the burnishers r cannot occupy the position shown in the drawings, where they would spread out the projection on the collar before it enters the lamp, 20 but are made to lie within the flaring opening in the plate L, and this is effected by means of the lever M, pivoted to one hub of the loose collar N, which incloses a second collar, N', rigidly secured to the shaft, so that the latter, 25 which is adjustably confined within its bearings u v, may be moved back until the burnishers occupy the position just described, and forward when desired. This forward movement of the shaft is caused to take place as 30 soon as the lamp-body has so far been made to approach the collar that the projection of the latter enters the orifice in the said lamp-body, when the arms E, which, owing to the 35 centrifugal force generated by the revolution 40 of the shaft, diverge as far as the chain H will permit, are made to approach each other by the action of the lever I, thus to spread out the burnishers r, which in turn spread the 45 projection of the lamp-collar against the inner edge of the opening in the lamp-body. A suitable stop, a, is provided for the lever M in the head of a pin driven into the cross-piece u.

It frequently occurs in the manufacture of 50 lamp-bodies, especially when they are composed of glass, that there will be inequality of its thickness in different parts, and when this occurs in the part against which the burnishers act, unless they were given, in addition to 55 their longitudinal movement with the shaft itself, an independent longitudinally-reciprocating motion within narrow limits, it is quite evident that, owing to the strain brought to bear, there would arise considerable liability 60 to breakage in attaching the collars. It is to obviate this and permit an automatic movement that the arms E and transverse plate s are made to operate as hereinbefore described.

The follower D consists of the base f, having 65 its lateral edges chamfered to fit and slide within the sides of the base of the machine,

which consist of strips likewise chamfered on their under and inner sides to receive the said base of the said follower and of the upright g, to receive which a part of the base f is cut 70 away, leaving two longitudinally-projecting arms, one on each side, which, being mere prolongations of the chamfered edges which slide between the sides of the base of the device, prepared in like manner to receive them, 75 as before stated, are to serve the purpose of affording greater smoothness in the motion of and security to the follower D. The upright is suitably braced, as shown at y. A clamp, e, presses the said follower to a strap, or endless band, O, by means of bolts and nuts d, of which but one is shown in the sectional view of the drawings. To change the position of the follower upon the endless band O, in order that the various lengths of lamp-bodies may 80 be accommodated between the face of the follower and the plate L, to any position different from that in which the device has been operating, it is only necessary to unscrew the nuts by a few turns, when a light tap upon the ends of 85 the bolts d will loosen the clamp e, and thus free the follower from the strap and permit its adjustment.

P P are pulleys provided with suitable bearings to facilitate the movement of the endless band, and R is a sectoral-shaped block working on a pivot, whose bearings are within two parallel blocks on the under side of the base of the device. To this block R one end of a lever, S, is secured, and to the other end of the 90 said lever is hinged a bar, S', terminating in a stirrup, c.

The operator will hold the levers K and M one in each hand to control the action of the burnishers, and with his foot in the stirrup 105 c, as the latter is forced down, move the follower forward till the burnishers have done their work, when the spring W forces it back to make ready for another operation, and the burnishers are made to collapse by allowing 110 to the centrifugal force full play upon the arms E in forcing the rod I, and thereby the chain G, inward.

T is a strip secured to the lever M and passing through a slot in the lever K, which, 115 while it permits independent movement of the levers, is provided with a pin, z, to afford a convenient stop for the lever K. This strip T is secured to the under side of the lever M, near the handle thereof, as being the most 120 convenient place to secure it.

What I claim as new, and desire to secure by Letters Patent, is—

1. In a machine for attaching collars to neckless lamp-bodies, the combination of the 125 following elements, viz: a suitable frame for supporting the operating mechanism, a rotary shaft carrying upon one extremity pivoted burnishers r, adapted, when brought together, to pass through the collar to be attached, 130 mechanism for bringing the said burnishers together, and mechanism for spreading the said

- burnishers apart for the purpose of turning up the inner end of the collar against the inner surface of the lamp-body, all substantially as described.
- 5 2. In a machine for attaching collars to neckless lamp-bodies, the combination of the following elements, viz: a frame for supporting the operating mechanism, a rotary shaft mounted in the said frame, a pair of burnishers, *r*, pivotally connected to the said shaft and projecting beyond the end of the same, mechanism for revolving the said shaft with the burnishers, mechanism tending automatically to prevent the burnishers from spreading, where-
15 by they may be passed through the collar, and mechanism for spreading the said burnishers in opposition to the said automatic mechanism, all substantially as described.
3. In a machine for attaching collars to neckless lamp-bodies, the combination of the following elements: a frame for supporting the operating mechanism, a rotary shaft mounted within the said frame, a pair of burnishers, *r*, pivotally connected to the said shaft and projecting beyond the end of the same, mechanism for rotating the said shaft and burnishers, mechanism operating automatically to prevent the said burnishers from spreading apart, mechanism for imparting to the said burnishers an independent longitudinally-reciprocating motion automatically, and mechanism for spreading the said burnishers apart at will, all substantially as described.
4. In a machine for attaching collars to neckless lamp-bodies, the hollow shaft *A*, supported in suitable bearings, transverse plate *s*, resting in slots in the said shaft and moving on a pivot passing through the said plate and through the shaft, and arms *t*, pivotally secured to the said plate at each end, one on each face thereof, the said arms expanding toward their other extremities into plates *C*, and at their said extremities forming burnishers *r*, in combination with mechanism for revolving the said shaft, and with mechanism for spreading apart the said burnishers at will, substantially as described and for the purpose set forth.
5. In a machine for attaching collars to neckless lamp-bodies, the hollow shaft *A*, supported in suitable bearings, the transverse plate *s*, resting in slots in the said shaft, and moving on a pivot passing through the said plate and through the shaft, arms *t*, pivotally secured to
- the said plate toward each end, and on opposite faces thereof, the said arms expanding toward their other extremities into plates *C*, and at their said extremities forming burnishers *r*, links *q*, each pivotally secured at one end to a plate, *C*, arms *E*, pivoted to the outer ends of the links and having their fulcrums in slots *p* of a collar, *F*, on the shaft, rod *I*, moving longitudinally within the shaft, chain or band *G*, connecting the rod *I* with the arms *E*, lever *K*, to operate the said rod, and mechanism for revolving the said shaft, substantially as de-
65 scribed and for the purpose set forth.
6. In a machine for attaching collars to neckless lamp-bodies, the combination of the following elements: a frame to carry the operating mechanism, the hollow shaft *A*, supported in bearings *u* *v*, transverse plate *s*, resting in slots in the shaft and moving on a pivot passing through the said plate and through the said shaft, arms *t*, pivotally secured to the said plate toward each end and on opposite faces thereof, the said arms expanding toward their outer extremities into plates *C*, and at their said extremities forming burnishers *r*, plate *L*, provided with an orifice to admit the passage of the burnishers *r*, and made flaring on its outer face and provided with the annular projection *h*, links *q*, each pivotally secured at one end to a plate, *C*, arms *E*, pivoted to the outer ends of the links, and having their fulcrums in slots *p* in a collar, *F*, on the shaft, chain or band *I*, collar *H*, having pulleys *o*, collars *N* and *N'*, lever *M*, secured to the hub of the said collar *N*, rod *I*, slotted near its outer extremity and confined in its movement by means of a pin, *n*, across the interior of the shaft near its rear end, and through the slot *m*, lever *K*, connected to the said rod by means of the pin *l*, having the head *K* to revolve in the socket underneath the cup *i*, driving-wheel *B*, follower *D*, moving in suitable guides in the frame, endless band or strap *O*, clamp *e*, and bolt *d*, provided with a nut, pulleys *P*, sectoral-shaped block *R*, lever *S*, attached at one end to the said block, and having hinged at the other a bar, *S'*, provided with a stirrup, *c*, and the spring *W*, as and for the purpose set forth.

ARTEMAS L. DAWSON.

In presence of—

ALONZO HASSON,
CHARLES H. FREEMAN.
